UNITED STATES PATENT OFFICE.

JACOB MARTIN LEE, OF HOUSTON, TEXAS.

RAILROAD-BED FOR TRESTLES.

SPECIFICATION forming part of Letters Patent No. 592,990, dated November 2, 1897.

Application filed December 29, 1896. Serial No. 617,847. (No model.)

To all whom it may concern:

Be it known that I, JACOB MARTIN LEE, a citizen of the United States, residing at Houston, in the county of Harris and State of Texas, have invented a new and useful Railroad-Bed for Trestles, of which the following is a specification.

This invention relates to trestle-bridges for railways provided with a road-bed of ballast under and in contact with the track cross-ties.

It is well known that a ballasted road-bed is preferable for the cross-ties for the reason that it affords a more elastic support for the track-rails than is the case where the cross-ties are supported directly on the trestle-bridge structure. Heretofore, however, trestle-bridges have not generally been provided with a road-bed of ballast for the reason that as heretofore constructed they have been very expensive and not susceptible of repair without destroying the road-bed to such an extent as to seriously interfere with the ordinary traffic of the road.

My invention overcomes these difficulties, and in addition to being designed for entirely new structures is also designed to meet the requirements of reconstruction and renewal of ordinary trestle-bridges on railroads.

In the accompanying drawings, Figure 1 is a side elevation of a portion of a trestle-bridge embodying my invention. Fig. 2 is a vertical transverse section of Fig. 1.

Similar numerals of reference designate corresponding parts in both figures of the drawings.

The substructure is arranged as in the ordinary pile or frame trestle-bridge. The trestles are indicated by 1 and the stringers by 2. The stringers are wooden beams substantially uniform in dimensions and of such size and number as to meet the requirements of the road and are preferably arranged so as to break joint or alternate on the caps 3 of the trestles. They are held in position by means of drift-bolts 4, extending through them into the caps. To the upper surface of the stringers is secured a flooring of planks, (indicated by 5.) The planks extend lengthwise at a right angle or diagonally to the line of structure, as may be desired, thereby affording longitudinal stiffness to the structure,

and at the same time permitting the removal of one of the planks without materially disturbing the road-bed. At each edge of the 55 flooring a guard-rail 6 is secured, the object of which is to confine the ballast on the flooring. These rails 6 extend the entire length of the structure and are secured to the flooring by bolts 7 or any other suitable removable fastening device in order that the rails may be detached from the flooring whenever necessary. On the flooring 5 is placed a bed of gravel or other suitable ballast 8, on which 60 rest the cross-ties 9.

10 represents the track-rails, secured to the ties in the ordinary manner. The ballast will also preferably be extended above the ties to cover them between the rails as a safeguard against burning cinders which may 70 fall from the locomotive, and the rails 10 will serve as guards to confine this part of the ballast in place.

From the foregoing description it will be seen that the structure presents a permanent 75 road-bed which can be adjusted and worked by the ordinary section forces and at the same time provides perfect protection against fire which might be caused by burning coal or sparks falling from the engine. It is also 80 obvious that the ties, the separate planks of the floor, or the stringers may be removed should they become decayed and be replaced with new ones without deranging or disturbing the road-bed in such a manner as to obstruct the traffic of the road.

In building an entirely new structure in accordance with my invention treated timber will be used for both the substructure and the superstructure. It is, however, obvious 90 that a superstructure constructed according to my invention may be placed on trestles now in use, thereby enabling the railroad companies to get the benefit of the full life of the timber in the trestles already in use, 95 and as these trestles can be gradually superseded by trestles of treated lumber the result will be that eventually a permanent structure of treated lumber will be made without entailing the heavy outlay incident to complete reconstruction at once.

The distinctive feature of my invention is that I provide in an economical manner a ballasted decked trestle, by which is meant a

- complete road-bed with a ballast under and between the ties and on top of a wooden structure, whereby I am enabled to use the ordinary track cross-ties, similar to those on every other part of the road, so that the surface and the alinement of the track can be maintained by regular section forces, and as all the pieces entering into the construction of the respective parts of the superstructure are respectively of substantially uniform dimensions, interchangeable, and easily removed the superstructure can be maintained in repair by the ordinary section forces at a minimum of expense.
- 15 It will be apparent that changes in the form, proportion, and minor details of construction may be resorted to without departing from the spirit or sacrificing any of the advantages of this invention.
- 20 Having thus described the invention, what is claimed as new is—
1. The combination with the trestles, and the longitudinal stringers detachably supported thereon and separately removable, of a transverse plank flooring supported directly on the stringers, a bed of ballast supported on said flooring, cross-ties and rails

supported directly upon said ballast, and longitudinally-arranged guard-rails detachably secured to the opposite edges of the flooring to confine the ballast, substantially as described.

2. The combination with the trestles and the longitudinal stringers supported thereon and separately removable and of uniform size, of a transverse plank flooring supported directly on the stringers, a bed of ballast supported on said flooring, cross-ties and rails supported directly upon said ballast, the ballast being extended above the ties to cover them between the track-rails, the latter serving as guards to confine that part of the ballast in place, and longitudinally-arranged guard-rails of uniform size detachably secured to the opposite edges of the flooring to confine in place the ballast below the ties, substantially as described.

In testimony that I claim the foregoing as my own I have hereto affixed my signature in the presence of two witnesses.

JACOB MARTIN LEE.
